UNITED STATES PATENT OFFICE.

WILLIAM W. DARLEY, OF PITTSBURG, PENNSYLVANIA.

APPARATUS FOR HANDLING ASHES AND OTHER MATERIALS.

968,542.

Specification of Letters Patent. Patented Aug. 30, 1910.

Application filed July 17, 1908. Serial No. 444,131.

To all whom it may concern:

Be it known that I, WILLIAM W. DARLEY, of Pittsburgh, Allegheny county, Pennsylvania, have invented a new and useful Apparatus for Handling Ashes and other Materials, of which the following is a full, clear, and exact description, reference being had to the accompanying drawings, forming part of this specification, in which the figure is a side elevation, partly broken away, of one form of apparatus embodying my invention.

My invention has relation to apparatus for handling ashes or other material of like character, and has been more particularly designed for use in the removal of ashes from the boilers of manufacturing plants, office buildings and other places where ashes are produced in considerable quantities.

My invention further relates to apparatus of this class, in which the ashes are drawn from the ash pits of furnaces by means of suction into a receptacle or hopper from which they may be discharged directly into a car or wagon, or from which they may be forced to a point of discharge by air pressure as described and claimed in my pending application Serial No. 408,511, filed December 30th, 1907.

My present invention is designed to provide means for effecting a complete separation of the ashes and air in the hopper of the receptacle into which the ashes are drawn by suction.

The precise nature of my invention will be best understood by reference to the accompanying drawings, in which I have shown one embodiment thereof, it being premised, however, that various changes may be made therein by those skilled in the art without departing from the spirit and scope of my invention as defined in the appended claims.

In this drawing, the numeral 2 designates the receptacle into which the ashes are drawn through the pipe 3, which leads to the ash pit or other point from which the ashes are to be removed.

4 designates a pipe of larger cross-sectional area than the pipe 3, and which is connected to a fan (not shown) arranged to exhaust the receptacle 2, whereby the ashes will be drawn therein through the pipe 3. The vessel 2 has a contracted lower portion 2^a, terminating in a discharge throat, 2^b, which may be arranged to dis-

charge directly into a wagon or other receptacle, or to which a discharge pipe leading to another point may be connected, as described in my said application.

The suction pipe 4, which is connected to the upper portion of the vessel 2, has an enlarged portion 5 which extends downwardly within the upper portion of the receptacle 2, its lower open end preferably terminating at the normal water level of a water pan 6, which is suitably supported within the upper portion of the vessel 2, and which is supplied with water by an inlet pipe 7. The baffles 5^a and 5^b are so arranged that 5^a has its lower portion projecting into the water in the pan 6, while 5^b preferably has its lower end at the water level. The spray pipe 7^a which is supplied by the water pipe 7^b is positioned to propel a constant spray of water down the outer face of the baffles 5^b. The pan 6 preferably has an inclined bottom 8 with a discharge opening 9 at its lower side, which is connected by an outlet pipe 10 with a sediment tank 11. This sediment tank has an outlet pipe 12 extending upwardly to about the normal water level of the pan 6, where it is connected to a discharge pipe 13.

14 is a supplemental discharge pipe leading outwardly from the upper portion of the water tank, and also connected to the discharge pipe 13 with a trap bend 15 therein, the purpose of this supplemental outlet being to provide for the overflow of the pan 6 in the event that the pipes 10 and 12 or either of them, should become clogged up. The sediment tank 11 is provided with the discharge bell 16, or with any other suitable means, by means of which it may be emptied and cleaned when desired.

17 designates a suitable scraper, whose actuating rod extends outwardly through the stuffing boxes 18, in the walls of the water tank 6 and of the receptacle 2, and which may be drawn back and forth on the inclined bottom of the water pan for the purpose of cleaning it.

19 designates a valve for controlling the connection between the pipe 4 and the interior of the receptacle, and which may be operated by a rack and pinion movement 20, or by any other suitable means.

21 is a water pipe which is arranged to discharge into the pipe 3 preferably near where the latter pipe discharges within the receptacle 2. I find it a great advantage

to wet the ashes in this manner before they are discharged into the receptacle, since in this way they can be thoroughly wet to the necessary extent with a minimum of water 5 and the presence of dust in the receptacle is avoided.

The water pan 6 is of considerably smaller diameter than the interior diameter of the upper portion of the receptacle 2 so as to 10 leave a surrounding air chamber. As will be seen the air which is exhausted from the receptacle 2, will pass upwardly around the water receptacle, and is forced to pass through the water pan, around the baffles 15 and through the water in pan 6 in order to enter the pipe 4, as indicated by the arrows. The water will therefore remove from the air all dust and ashes which might otherwise be carried off with the exhaust to the fan. 20 It is the provision of this water pan arranged in the manner described which enables me in most cases to dispense with the water pipe 21, which has heretofore been necessary to prevent dust and ashes being 25 carried over the fan, and which necessitates the constant mixture of water with the ashes as they are discharged, or previous to their discharge.

I do not limit myself to the exact arrangement of the parts which I have shown and described, it being obvious that various changes may be made in detail thereof without departing from my invention. Thus, the receptacle 2 may be of any desired character; the water pan may be differently constructed, and the sediment tank can be in some cases omitted.

What I claim is:—

1. In apparatus of the character described, a receptacle, an inlet pipe leading therein to convey the material to the receptacle, an exhaust pipe connected to the receptacle, a water pan supported in the receptacle above the inlet pipe, baffling plates 45 surrounding the mouth of the exhaust pipe and within the outer wall of the water pan, and means for maintaining a normal level of water in said pan; substantially as described.

2. In apparatus of the character described, a receptacle, an inlet pipe leading therein to convey the material to the receptacle, an exhaust pipe connected to the receptacle and extending therein, a water 55 pan within the receptacle and surrounding the inner end of the exhaust pipe, and means for maintaining the normal water level of said pan above the mouth of the exhaust pipe; substantially as described.

3. In apparatus of the character described, a receptacle, an inlet pipe extending therein to convey the material to the receptacle, an exhaust pipe connected to the receptacle, and a water pan surrounding the 65 inner end of the exhaust pipe and providing

a water seal through which the air exhausted from the receptacle must pass in entering said pipe; substantially as described.

4. In apparatus of the character described, a receptacle, an inlet pipe extending therein to convey the material to the receptacle, an exhaust pipe communicating with the receptacle above the point of discharge of the inlet pipe, and a water pan 70 surrounding the mouth of the exhaust pipe and providing a water seal therefor, said pan having a sediment discharge pipe extending within the receptacle; substantially as described.

5. In apparatus of the character described, a receptacle having an inlet pipe extending therein to convey the material to the receptacle, an exhaust pipe connected to the receptacle, a water pan within the receptacle 85 forming a water seal for the mouth of the exhaust pipe, said pan having an inclined bottom, a discharge pipe connected with said pan, a sediment tank into which the discharge pipe leads, and an overflow pipe 90 for the sediment tank extending upwardly to about the normal water level of the water in the pan; substantially as described.

6. In apparatus of the character described, a receptacle having an inlet pipe 95 extending therein to convey the material to the receptacle, an exhaust pipe connected to the top of the receptacle, a water pan within the receptacle and above the inlet pipe, said water pan forming a water seal 100 for the mouth of the exhaust pipe, the pan having an inclined bottom, a sediment discharge pipe connected to the said pan, a sediment tank into which the discharge pipe leads, and an overflow pipe for the sediment 105 tank extending upwardly to about the normal water level of the water in the water pan, together with a secondary overflow pipe leading from the upper portion of the water pan; substantially as described.

7. In apparatus of the character described, a receptacle, an inlet pipe extending therein to convey the material to the receptacle, an exhaust pipe connected to the receptacle, a water pan above the inlet pipe 110 and forming a water seal for the mouth of the exhaust pipe, together with means for maintaining a normal level of water in said pan above the mouth of the exhaust pipe, and at least one baffle arranged above the 115 water pan and adjacent to the mouth of the exhaust pipe; substantially as described.

8. In apparatus of the character described, a receptacle having an inlet pipe extending therein to convey material to the 120 receptacle, an exhaust pipe connected to the receptacle and extending therein, a water pan within the receptacle and above the inlet pipe, said water pan surrounding the mouth of the exhaust pan, means for main- 125

taining a normal level of water in said pan above the mouth of the exhaust pan, a baffle arranged above the water pan and adjacent to the mouth of the exhaust pipe, a sediment discharge pipe leading from the water pan to the outside of the receptacle, and a scraper within the water pan having an actuating rod extending through the wall

of the water pan and the receptacle; substantially as described.

In testimony whereof, I have hereunto set my hand.

WILLIAM W. DARLEY.
